UNITED STATES PATENT OFFICE.

WILLIAM CLAYTON CORYELL, OF YOUNGSTOWN, OHIO, ASSIGNOR TO THE GENERAL FIREPROOFING COMPANY, OF YOUNGSTOWN, OHIO, A CORPORATION OF OHIO.

BUILDING FABRIC.

1,354,024.

Specification of Letters Patent. Patented Sept. 28, 1920.

Application filed July 9, 1919. Serial No. 309,629.

To all whom it may concern:

Be it known that I, WILLIAM CLAYTON CORYELL, citizen of the United States, residing at Youngstown, in the county of 5 Mahoning and State of Ohio, have invented certain new and useful Improvements in Building Fabrics, of which the following is a specification.

This invention relates to building material employed chiefly as a substitute for wooden and metal lathing and particularly to a building material or fabric of that character having a novel form and novel reinforcement which materially improve the 15 structural and functional characteristics thereof.

Certain important objects are achieved by the present invention. Among these objects are primarily to provide a building 20 material or fabric of a cheap and simple construction and which shall be available generally as a form or matrix for plastered walls, partitions, ceilings and other portions of a building, as well as susceptible of being 25 used alone as a panel material. Also, it is proposed to provide a material or fabric of such structural conformation as to provide an effective and extensive keying surface for receiving and holding the wall plaster, 30 stucco, cement or other surfacing material. Furthermore, it is also an important object of the invention to construct the new building material in such form as to facilitate and cheapen the cost of manufacture of an 35 article of this kind while at the same time admitting of a very effectual disposition of reinforcing elements which not only contribute to the stiffening and strengthening of the product itself, but which also will 40 afford a substantial reinforcement and support for the cementitious material when hardened.

Another object of the invention is to construct a building material or fabric in which 45 the expansion and contraction will be so little as to be a negligible consideration, and also to embody with the material during its manufacture elements or means which will render the same both waterproof 50 and fire-resistant, and which will not be subject to warping when the wet plaster is applied.

With these and other objects in view 55 which will readily appear to those familiar with this art as the particular features of

the invention are better understood, the invention consists in the novel construction, combination and relation of parts herein-after more fully pointed out, illustrated and claimed.

Though susceptible of a wide range of modification as to essential features, a few preferred and practical embodiments of the invention are shown in the accompanying drawings, in which:—

Figure 1 is a plan view of a building fabric embodying the present invention.

Fig. 2 is an end edge view of the fabric unit shown in Fig. 1.

Figs. 3 and 4 are cross-sectional views of 70 the fabric respectively on the lines 3—3 and 4—4 of Fig. 1.

Fig. 5 is a side edge view of a piece or unit of fabric shown in Fig. 1.

Figs. 6 and 7 are longitudinal sectional 75 views of the fabric respectively on the lines 6—6 and 7—7 of Fig. 1.

Fig. 8 is a plan view of a panel form of the fabric or material in which the keying openings through the sheet are omitted. 80

Like references designate corresponding parts in the several figures of the drawings.

A building material or fabric constructed in accordance with the present invention primarily includes, in combination, a novel 85 consolidation of metallic reinforcing and holding members for the plastic or equivalent material with a flexible body sheet or element carried with said members. A structure of this kind is available as a substitute for wooden and metallic lathing and possesses several advantages thereover, principal among which are cheapness and simplicity of manufacture and the adaptability of such a material to the use of metallic reinforcement which effectually reinforces the wall and constitutes permanent supporting elements therefor, at the same time contributing materially to an effectual keying of the plaster onto the body sheet. Furthermore, a consolidation of the flexible body sheet and the metallic members in the material contemplated by the present invention provides a fabric which can be made to respond to all building requirements for such 95 a material.

The flexible body sheet or element, forming a part of the present invention, is designated in the drawings by the numeral 1 and this is preferably a fibrous material made 110

impervious to water by being impregnated with a suitable waterproofing compound such for instance as silicate of soda and asphaltum or other known waterproofing substances. A sheet material of this kind and character are the well known commercial roofing papers, but it would of course be understood that in carrying forward the invention any equivalent material could be utilized, though the preferable embodiment of the invention includes a flexible sheet of fibrous material given suitable treatment to render the same substantially waterproof and therefore resistant to the warping influence of the wet plaster. Also it is preferable to prepare the flexible body sheet in such a manner as to render the same fire-resistant as well as to afford better adhesion between the fabric and the plaster. This may be accomplished by various expedients one of which would be to surface the sheet, before the same is ready for use, with an earthy or non-combustible substance as for instance by rolling or otherwise pressing fine sand, dust or equivalent dry granulated material into the surface, and subsequently dipping the sheet into a liquid form of artificial stone thereby producing an artificial stone-like surface on the fabric. Any well known artificial stone composition may be employed for this purpose, such as a mixture of silicate of soda, infusorial earth and oxid of zinc.

Furthermore, in the preparation of the flexible body sheet or element it is desirable, under certain conditions, to accelerate the drying of the surfacing liquid and while different expedients obviously could be resorted to for that purpose a simple and effective method proposed is to sprinkle dry non-combustible dust against the wetted surface, causing the dust to adhere to such surface and naturally hasten the drying thereof. This treatment, moreover will to some extent increase the stone-like appearance of the fabric as well as thicken the non-combustible coating or surface over the combustible material of the fabric.

It is regarded as desirable, as indicated, to prepare the body sheet so as to make the same waterproof and fire proof and also not subject to warping when the wet plaster is applied, but the distinctive and important structural characteristic of the invention is the novel manner in which this body sheet is consolidated or combined with the metallic reinforcing and holding members. These metallic members or strands may consist of metal wires, rods or strips of any suitable gage according to the weight and stiffness required for the material or fabric in the particular building operations for which it may be specified. But, regardless of the size and form of the metal wires, rods or strips the same are interwoven with the body sheet

in such a manner as to be disposed and exposed upon both sides thereof, thus providing uniformity of reinforcement throughout the fabric as well as throughout the plaster coat or body supported thereby. The interweaving of the metallic reinforcing members with the body sheet may be accomplished in any suitable manner by machinery or otherwise, but the operation necessarily involves what may be termed a threading of the metallic members through the sheet from end to end or side to side thereof according to the form and dimensions of the sheet.

However, for illustrative purposes there is shown in the drawings a fabric unit embodying the novel reinforcement, that is, a piece or section of fabric made in accordance with the present invention. Referring to this unit of construction shown particularly in the group of Figs. 1 to 7 inclusive it will be observed that the flexible fibrous body sheet 1 may be provided with a plurality of rows of threading holes 2, the series of holes in each row being in longitudinal alignment and being adapted to have a metallic reinforcing member 3 woven or threaded therethrough so that portions of the reinforcing member will be alternately disposed upon opposite sides of the body sheet with the result of giving the uniform reinforcement throughout the fabric, as well as making the latter reversible so that the plaster coat may be applied to either side thereof.

The weaving or threading of the individual metallic reinforcing members 3 through the row of holes provided therefor involves certain structural features which are of practical importance. In the first place it will be observed from the group of Figs. 2 to 7 inclusive that the flexible body sheet is given a crimped formation, forming shallow undulations laterally of the sheet shown in Figs. 2, 3 and 4, and producing, in the longitudinal plane of the reinforcing members 3, a corrugated effect. This corrugated effect provides within the longitudinal plane of each reinforcing member, upon opposite sides of the sheet, the depressions or sinks 4 within which lie the exposed portions of the reinforcing members. This is plainly shown in Fig. 6 of the drawings and from that figure it will also be observed that the peculiar crimped formation described has the effect of bringing the threading holes of each row into longitudinal aligned communication so that the reinforcing wire or rod may be threaded in a straight line therethrough, and may be maintained straight in order to have its full efficiency as a reinforcing member as well as facilitating the operation of manufacturing the fabric.

Although the threading holes have been

- referred to as a desirable means to facilitate the weaving of the reinforcing members through the body sheet it is to be understood that my invention is not limited to 5 this detail of construction because the same structural result can be accomplished by merely slitting the sheet at the locations of the holes 2 or by employing a sharpened reinforcement as indicated at α in Fig. 6 which 10 could readily pierce through the side walls of the corrugations referred to, as may be plainly seen from the said Fig. 6 of the drawings.
- In addition to the advantages afforded in 15 the manufacture of the improved fabric by crimping the body sheet and weaving or threading a reinforcing member or members therethrough, it will be seen from Fig. 6 of the drawings that the depressions or 20 sinks 4 in which the exposed portions of the reinforcing members lie constitute seats in which the wet plaster locks itself on or about the reinforcement, thus contributing quite materially to the effective keying of the plaster 25 coat onto the fabric. This keying of the plaster coat to the fabric may be materially increased by providing the fabric at suitable intervals therein, preferably alternately with the rows of reinforcements 3, 30 with a plurality of keying openings 5 constituting keying elements through which the lugs of plaster extend. For this phase of the invention any equivalent supplementary keying elements or means may be utilized to 35 supplement or insure the adhesion of the plaster or surfacing material to the fabric.
- It will of course be understood that the herein described fabric or material may be rendered available for use as a cheap panel 40 construction by simply preparing the same with the threaded or woven reinforcements without keying openings or equivalent expedients associated with the sheet. This is illustrated in Fig. 8 of the drawings.
- 45 From the foregoing it is thought that the construction, use and advantages of the herein described building fabric or material will be readily apparent to those familiar with this subject without further description but 50 it will be understood that changes in the form, proportion and minor details of construction may be resorted to without departing from the principle or sacrificing any of the advantages of the invention.
- 55 I claim:—
1. A building fabric consisting of a body sheet crimped to form transverse rows of shallow undulations, and the hills and valleys of adjacent rows being arranged in staggered relation to produce longitudinal 60 rows of corrugations, and metallic reinforcing members threaded through the corrugations of each longitudinal row.
  2. A building fabric consisting of a body sheet crimped to form transverse rows of relatively shallow undulations and the hills and valleys of the adjacent rows being arranged in staggered relation to produce longitudinal rows of hills and valleys having relatively abruptly inclining sides, and metallic reinforcing members threaded through the said inclining sides of the hills and valleys of each longitudinal row.
  3. A building fabric consisting of a body sheet crimped to form a series of regular 75 hills and valleys laterally of the sheet and arranged in transverse parallel rows, the hills and valleys of adjacent rows being arranged in staggered relation to produce longitudinal rows of corrugations, the inclining 80 sides of which are relatively steep compared with the corrugations produced by the laterally extending hills and valleys, and metallic reinforcing rods threaded through the relatively steep sides of the corrugations of 85 each longitudinal row.
  4. A building fabric consisting of a body sheet crimped to produce transverse rows of staggered corrugations and provide longitudinal rows of uniform corrugations, and 90 metallic reinforcing elements threaded through the walls of the corrugations of the longitudinal rows to lie in part respectively on opposite sides of the sheet.
  5. A building fabric consisting of a body 95 sheet crimped to produce a plurality of transverse rows of corrugations, the crowns of the corrugations of the adjacent rows being arranged in staggered relation to produce regular longitudinal rows of corrugations, and metallic reinforcing members threaded through the regular corrugations of the longitudinal rows, and the hills and valleys of the said laterally arranged rows of corrugations being provided with keying 100 openings.
- In testimony whereof I hereunto affix my signature in the presence of two witnesses.
- WILLIAM CLAYTON CORYELL.
